Primary Examiner — Barbara Fox*Assistant Examiner* — Lilyana Bekic(74) *Attorney, Agent, or Firm* — Knobbe, Martens, Olson & Bear LLP(57) **CLAIM**

The ornamental design for a canister for collecting wound exudate, as shown and described.

DESCRIPTION

FIG. 1 is a top, front, and left side perspective view of a canister for collecting wound exudate.

FIG. 2 is a bottom, rear, and right side perspective view thereof.

FIG. 3 is a top plan view thereof.

FIG. 4 is a bottom plan view thereof.

FIG. 5 is a left side view thereof.

FIG. 6 is a right side view thereof.

FIG. 7 is a front view thereof; and,

FIG. 8 is a rear view thereof.

The broken lines in the drawings illustrate portions of the canister for collecting wound exudate which form no part of the claimed design.
